Specification for Design.

Patented Aug. 5, 1919.

Application filed January 27, 1919. Serial No. 273,495. Term of patent 14 years.

To all whom it may concern:

Be it known that I, LEONARD R. MARTELL, a citizen of the United States, residing at Detroit, in the county of Wayne and State of Michigan, have invented a new, original, and ornamental Design for a Compression, Combustion, and Spark-Plug Tester, of which the following is a specification, reference being had to the accompanying drawing, forming part thereof.

Figure 1 is a side elevation of a com-

pression, combustion and spark plug tester, showing my new design, and

Fig. 2 is a perspective view of the same.

I claim:

The ornamental design for a compression, combustion and spark plug tester, as shown.

LEONARD R. MARTELL.
